UNITED STATES PATENT OFFICE

2,559,309

COUNTING TOY

Clarence E. McCormick, Poland, Ohio

Application January 30, 1946, Serial No. 644,249

3 Claims. (Cl. 46—118)

1

This invention relates to a toy and more particularly to a counting toy.

The principal object of the invention is the provision of a toy incorporating a counting mechanism therein and means externally thereof for actuating the said counting mechanism.

A further object of the invention is the provision of a counting toy incorporating means for visually indicating each rotation of an exterior portion of the toy.

A still further object of the invention is the provision of a counting toy incorporating means for audibly indicating each rotation of an exterior portion of the toy.

A still further object of the invention is the provision of a counting toy incorporating means for audibly and visually indicating each rotation of an exterior portion of the toy.

The counting toy shown and described herein has been designed to provide a simple and attractive toy for a child which will facilitate the child's learning various numerals, particularly in orderly sequence, as in counting. The toy has been designed in the form of an animal having an exterior portion such as a tail which may be revolved by the child and which in turn will impart suitable movement to a counting device within the toy to provide a visual accumulative counting action. The counting toy may also be employed for any counting operation which may be performed manually thereby making the toy an attractive, useful, as well as educational article.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a top plan view of a counting toy.

Figure 2 is a side elevation of one of the body members of the counting toy taken on line 2—2 of Figure 1.

By referring to the drawings and Figures 1 and 2 in particular, it will be seen that a counting toy has been disclosed which consists of a representation of an animal such as a pig, and is formed of two solid body portions 10 and 11, respectively, the body portions being connected

2

to each other by means of dowel pins 12. The dowel pins 12 engage registering openings 13 in the respective body portions 10 and 11. The body portions 10 and 11 have oppositely disposed, matching, cutaway sections 14 and 15, respectively, which form, when the counting toy is in assembled position as shown in Figure 1, a cavity in the otherwise solid body and which cavity is adapted to receive a counting mechanism. The cutaway sections 14 and 15 have portions extending outwardly through the back of the respective body portions 10 and 11 so as to provide for the visual observation of the counting mechanism disposed within the cavity so formed. A section of transparent material 16 forms a closure with respect to the opening in the back defined by the upwardly extending portions of the cutaway sections 14 and 15, and the section of transparent material 16 is in engagement with grooves 17 formed in the edges of the cutaway portions.

The counting mechanism positioned within the cavity in the counting toy consists of a shaft 18, one end of which is disposed in a socket 19 in the solid body portions 10 and 11 and the other end of which extends outwardly of the body portions 10 and 11 and is bent in the form of an animal's tail, as indicated by the numeral 20. The shaft 18 carries three counting wheels 21 freely mounted thereon, the wheels being indicated by the numerals 21, 22 and 23. A fourth wheel 24 is also positioned on the shaft 18 but is fastened thereto so that it may be employed to drive pinions disposed between the wheels and indicated by the numerals 25, 26 and 27. A fifth wheel 28 is also positioned on the shaft 18 and forms means spacing the counting wheels 21, 22 and 23 so as to cause them to register with the said opening for visibility therethrough. It will be observed that the pinion 25 is positioned on a spacing disc 28 also positioned on the shaft 18 and a portion 29 of which extends below the several wheels and engages registering openings in the respective body portions 10 and 11 so as to hold the pinion supporting spacing disc 28 in stationary position with respect to the shaft 18.

It will thus be seen that when the tail 20 is turned one revolution the shaft 18 will revolve one revolution and the wheel 24 will revolve one revolution as it is fixed to the shaft 18. During this one revolution, the pinion 25 carried on the spacing disc 28 will engage an internally positioned offset in the wheel 24 and thereby be revolved once and impart that motion to the wheel 23 thereby moving it one-tenth of a revolution.

The wheels 21, 22 and 23 have numerals positioned about their periphery from 1 to 0, inclusive, and one of these numerals will therefore register beneath the transparent window 16; for example, the numeral 1. Ten revolutions of the tail 20 will revolve the wheels ten times and at each revolution the wheel 23 will revolve one-tenth of a revolution and bring a new and higher numeral into view beneath the window 16. When the tenth revolution occurs, the pinion 26, which is positioned between the wheels 22 and 23 by means of a supporting disc 30 and held stationary with respect to the body portions 10 and 11, will impart the same movement to the wheel 22 thereby urging it to the first position so that the numeral 10 appears, the numeral 1 being on the wheel 22 and the 0 being on the wheel 23, both in registry beneath the window 16. This mechanism is exactly the same as that used in speedometers in motor vehicles, and as its construction and mechanism is well known in the art, it is not further illustrated or described herein.

By referring again to the wheel 24, which is positioned on the shaft 18, it will be observed that there is a pin 31 extending outwardly therefrom into the adjacent cavity formed by the oppositely disposed, cutaway sections 14 and 15 in the body portions 10 and 11, respectively. This pin is provided to form an audible sound with each rotation of the tail 20 which revolves the wheel 24 one turn and the audible sound is created by the pin 31 engaging one end of a vibrating spring 32 which is positioned within a cutaway section 33 in the body portion 10. It is held therein by means of a staple 34 and also by reason of an end 35 of the spring 32 being turned at right angles to the remainder thereof and inserted into an opening 36 in the body portion 10.

It will thus be seen that a counting toy has been devised which incorporates an attractive toy with a useful and educational counting mechanism which is particularly helpful in teaching a child to count, as it enables the child to hear and see the results of the motion imparted to the counting mechanism. As with similar counting mechanisms as employed as in speedometers, the counting mechanism may be reset by revolving the tail 20 and master shaft 18 backwardly.

It will be obvious to those skilled in the art that a counting toy may be made with one counting wheel in it or a number of counting wheels so that any desired number may appear in the window opening thereof. It will also be seen that

the toy is of simple and durable construction and that it may be economically formed and hence widely distributed.

Having thus described my invention, what I claim is:

1. In a counting toy a pair of oppositely disposed registering solid body members simulating an animal form, matching cavities formed in the said body members, a counting mechanism positioned in the said cavities, the said counting mechanism including an axially extending supporting and motivating shaft, one end of the said shaft extending outwardly of the said body members and shaped to simulate an animal's tail, registering openings in the said body members so that the counting mechanism may be viewed therethrough.

2. A toy including a body simulating an animal having a cavity formed therein, an opening in the said body communicating with the said cavity, a counting mechanism positioned in said cavity in registry with said opening, a portion of the said counting mechanism extending outwardly from the said body and simulating an animal's tail to provide for the manual actuating of the said mechanism by the manipulation of the said extended tail simulating portion.

3. A toy including a body representing an animal and having a cavity formed therein, an opening in the said body communicating with the said cavity, a counting mechanism positioned in said cavity, a portion of the said counting mechanism extending outwardly from the said body in the form of the tail of the said animal, to provide for the manual actuating of the said mechanism by the manipulation of the said extended portion.

CLARENCE E. McCORMICK.
